UNITED STATES PATENT OFFICE

150,926

DESIGN FOR A TRANSPORT AIRPLANE

Vincent J. Burnelli, Red Bank, N. J.

Application March 6, 1946, Serial No. 127,154

Term of patent 14 years

(Cl. D71—1)

To all whom it may concern:

Be it known that I, Vincent J. Burnelli, a citizen of the United States, residing at Red Bank, in the county of Monmouth and State of New Jersey, have invented a new, original, and ornamental Design for Transport Airplanes, of which the following is a specification, reference being had to the accompanying drawing, forming part thereof.

Figure 1 is a top plan view of a transport airplane, showing my new design.

Fig. 2 is a front view of Fig. 1.

Fig. 3 is a side elevation, and

Fig. 4 is a bottom perspective view.

I claim:

The ornamental design for a transport airplane, as shown.

VINCENT J. BURNELLI.
